B. T. TRIMMER.

Grain Cleaner.

No. 12,657.

Patented April 3, 1855.

UNITED STATES PATENT OFFICE.

B. T. TRIMMER, OF PARMA, NEW YORK.

GRAIN-CLEANER.

Specification of Letters Patent No. 12,657, dated April 3, 1855.

To all whom it may concern:

Be it known that I, BENJAMIN T. TRIMMER, of Parma, in the county of Monroe and State of New York, have invented certain new and useful Improvements in Scouring Machines for Cleansing Grain; and I do hereby declare that the following is a full and exact description thereof, reference being had to the accompanying drawings, making part of this specification, and to the letters of reference marked thereon, and of said drawings—

Figure 1 is an elevation of one side. Fig. 2 is an elevation of the opposite side. Fig. 3 is an elevation of the right hand end of Fig. 1. Fig. 4 is an elevation of the left hand end of Fig. 1. Fig. 5 is a plan of the whole machine. Figs. 6, 7 and 8 are plans and a sectional elevation of the scouring apparatus. Fig. 9 is a sectional elevation of the screen showing its internal construction, the crown wheel by which it is driven and the friction rollers upon which it runs.

Same letters referring to like parts in all the figures.

As it is in general designed to connect this machine with a screening machine, I have shown and described the latter for convenience sake, but do not consider the present application for Letters Patent to apply thereto.

The nature of my invention consists in certain new methods of constructing and arranging teeth or beaters in scouring machines with india rubber or gutta percha scrolls and sucking blasts whereby the grain is effectually cleansed from all impurities in a much more perfect manner and with much greater ease than by the means hitherto in use.

To enable others skilled in the art to understand, make and use my invention I will proceed to describe its construction and operation, which may best be done by detailing the various operations which the wheat undergoes from its entrance into the machine to its exit therefrom.

The wheat as it comes from the separator passes into the spout A and through it into the screen. During its passage through the pipe A it is subjected to a blast passing through the pipe B which clears it of chaff, white-caps, etc. The screening process is performed by a combination of several concentric screens connected together and revolving upon the friction rollers (r, r, Fig.

3). v (Fig. 9) is a groove in which another and corresponding set of friction rollers work.

The inner screen C is formed of sheet metal and is inclined at a slight angle so that the end opposite to that at which the wheat enters is the lowest. The wheat will consequently roll down the inner screen, passing through the holes therein, while all large bodies such as nails, wheat-ears, etc., being too large to pass these holes, will roll down to the lower end of this screen and there pass off by the spout s. The inner screen passes through the wheel w by which the whole screen is revolved, and in order to make a sufficiently tight joint in the case for directing all the dirt to the spout s there is a hoop or flange attached to this wheel or to the frame to which it is attached, which hoop fits and revolves within another hoop (h) attached to the outer case of the screen.

It is evident that as the whole screen revolves the wheat which falls through the holes in the inner screen near its entrance will partially fall back and through the same screen. This is prevented in the latter portion of its descent by the mode of punching the holes in the screen, the metal not being cut away but simply cut on three sides and raised as will easily be seen from the drawing, Fig. 9. The holes are there seen covered by a kind of valves which while they permit the free exit of the wheat effectually prevent its return as it falls from the upper side of the second screen. After passing through the first screen the wheat, now separated from all the grosser impurities but still mixed with small seeds, chess, etc., falls on to a second screen revolving exteriorly to the first. This screen is conical to such a

degree that the underside thereof forms an inclined plane of about the same depression as the first screen but reversed, notwithstanding the contrary inclination of its axis. For a certain portion of its length toward the left hand (as seen in the drawing, Figs. 2 and 9) the holes in this screen are so small as to prevent the passage of the wheat but allow all lesser impurities free egress. These lesser seeds and impurities are caught by the conical sheet D which has no holes but carries everything that falls on it to the holes or slots d, d, in the end of the screen, which holes or slots lead to the chamber E (Fig. 9); whence everything passes off by the spout S. Toward the lower portion of

the second screen, however, immediately beyond the point of junction of the conical sheet D, the holes are made larger and are covered by the same valve-like coverings used in the first cylindrical screen. The wheat passing through these holes and prevented from returning by the valve-like coverings falls on to the fine cylindrical screen seen exterior to all the others. This screen being cylindrical and its axis having an inclination corresponding to that of the inner cylindrical screen, the wheat will roll along it until it reaches the end opposite to that at which it entered, and passing out at the point G into the spout I (seen in Figs. 1, 3, and 9) passes into the scouring machine. All small seeds and lesser impurities meanwhile passing through the exterior screen on to the sheet K and thence into the spout L L which carries them to any proper receptacle. While passing through the internal cylindrical screen the wheat is subjected to the action of a blast from the fan which enters by the pipe Q and passes out at the spout R. A damper or hinged apron may be placed in this spout so as to return the dirt and light grain to the chamber T.

The scouring apparatus consists of a series of two or more hollow conical pustias having spring teeth formed and attached as shown in sectional elevation in Fig. 6 and in plan in Fig. 7. These teeth are formed of thin sheet steel curved and attached as there shown; some of these teeth are formed 35 similar to a rasp as there shown; others are armed with pointed teeth while some are quite plain. The concave also is provided with teeth or beaters cast thereon or formed of suitable material and attached thereto 40 and against which the wheat is rubbed or scraped by the spring teeth on the convex. The wheat passes from the spout I into the top of the scouring machine, being subjected in its passage to another blast derived from 45 the box H above the fan and passing along the pipe F. The wheat is driven by centrifugal force over the plate (m) and thence down the sides between the concave and convex cones. As it is here that the smut-balls 50 are broken and the dust removed from the ends of the berries, and as it is essential that this dust should be immediately removed I suck the air through the holes in the top of the smut mill down between the concave and 55 convex and through a series of small holes in the said convex (to which the spring teeth are attached)—too small to permit the passage of the wheat. The air thus carries all dust and dirt down the central pipe and 60 along the tube P (seen in red lines in Fig. 1) to the fan.

The teeth or beaters on the concave may be serrated as in X (Fig. 6) or plain as seen on the opposite side.

65 After passing between the two cones and

having the loose smut and dust removed by the action of the sucking blast the wheat descends to the scouring plate (n) across which it is scrolled to the center by the spiral scroll (z z) formed of gutta percha or india-rubber. This scroll exerts a further wiping action on the wheat and delivers it on to the upper plate of the next scouring machine whence it is driven by centrifugal force to the next series of teeth and beaters and after passing through the same process as formerly described it is delivered by another scroll through the aperture U into the spout g. The last scroll is shown in plan in Fig. 8 where the brown color shows the india rubber. In passing through the spout g the wheat is again subjected to the action of a sucking blast which passes through the tube (h) and into the top of the fan through the square pipe (t). The air being drawn over and around the bent sheet (N) in the tube (M) the light grain &c. will chiefly fall to the bottom of this tube and when it has accumulated sufficiently will overcome the spring, open the trap door or valve and escape.

The air which passes through the pipe (h) is admitted through the aperture (b) which when no wheat is passing is closed by the plate (C). (Those parts which lie behind the square pipe (P) are shown in red lines Fig. 6). But the weight of the wheat lying on the valve (y) will press down the spring seen below it and will not only open a passage for the wheat but will also admit air through the aperture (b) by lowering the plate (c). The spring is regulated by a screw shown beneath it.

I will now proceed to describe the mode of operating the machine and those details which have not been hitherto noticed.

A band from any convenient source of power passing around the pulley (1) on the shaft (2), which passes through the scouring machine, will cause it to revolve and give motion to the fan through a band passing over the pulleys (3) and (4).

A pinion (5) on the shaft (2) drives the crown wheel which is seen attached to the screen in Fig. 9.

(6) Fig. 4 is a spring valve to regulate the blast passing through the pipe.

(7) is a screw for raising and lowering the bridge tree upon which the shaft (2) rests. By these means the scouring teeth and india rubber scroll are brought to bear more heavily on the wheat which may be done without any danger of bruising the berries as the spring teeth and india rubber scroll are yielding. The india rubber is attached to the under plate by means of sheet-iron flanges as will be easily understood from the drawing. The screens are best constructed in two halves so as to slip out between the ends.

(8) is a handle to move a valve regulating the force of the blast in the pipe F.

Having thus described my invention, what I claim therein as new and desire to secure 5 by Letters Patent is—

The construction and arrangement of the india rubber scroll and spring teeth regu-

lated by the bridge-tree for the purpose and in the manner substantially as described.

B. T. TRIMMER. [L. s.]

Signed in presence of—

JOHN PHIN,

JAS. M. CUYKENDALL.
